UNITED STATES PATENT OFFICE

WESLEY V. MORGAN, OF ROCHESTER, NEW YORK, ASSIGNOR TO GENERAL RAILWAY SIGNAL COMPANY, OF ROCHESTER, NEW YORK

CAR RETARDER FOR RAILROADS

Application filed February 24, 1930. Serial No. 430,714.

This invention relates in general to car shoes 5 and 6, in any desired manner, as for retarders of the track brake type, and has more particular reference to an improved form of brake shoe and brake shoe beam in such retarders whereby to obviate all possibility of derailment of a car.

It is most important in car retarders of the type concerned in this invention, that a car passing through the retarder be prevented from climbing out of the retarder and being derailed, with very likely damage to the retarder and the car.

With the above and other considerations in mind, it is proposed, in accordance with the present invention, to provide a form of retarder shoe and shoe beam such as to absolutely prevent any derailment of any car passing through the retarder.

More specifically, it is proposed in accordance with this invention to form the brake shoe and the shoe beam so as to have an upstanding flange at the inner side of each car wheel whereby, if a car should climb out of this form of retarder, it will be impossible for the car to run off of the top of the retarder.

Further objects, purposes and characteristic features of the present invention will appear as the description progresses, reference being made to the accompanying drawing, showing, solely by way of example, and in no manner whatsoever in a limiting sense, two forms which the invention can assume. In the drawing:—

Fig. 1 is a sectional diagrammatic view of one form of the invention.

Fig. 2 is a sectional diagrammatic view, to a larger scale, of the form of invention shown in Fig. 1.

Fig. 3 is a sectional diagrammatic view of a slightly modified form of the invention.

Fig. 3A is a fragmentary view of a further modified form.

Referring now to the drawing, and first to Fig. 1, there are here shown two track rails 1 which constitute a stretch of single track, on which roll wheels 2 of a car to be retarded.

At each side of each track rail 1, are shoe beams 3 and 4, on which are mounted brake

arms 5 and 6, respectively, each arm being carried on pivots 8 and 9, the upper end of each arm being received in a socket 10 in the respective brake beam, while the lower ends of each pair of arms has positioned therebetween a compression spring 11, which is preferably pretensioned so as to contain a trapped, or initial, tension.

An operating bar is shown at 12, for operating an angle lever 13, pivoted in fixed supports 14 and pivoted at 15 to a cross rod 16, which passes transversely below the track rails 1, and has fastened to it the chairs 17 as by screws 18, the pivots 9, carrying the arms 5, being mounted in the chairs 17 whereby to move therewith.

On moving the bar 12 in a direction at right angles to the plane of the paper, cross rod 16 is moved transversely of the track rails to thereby move the pivot points 9 either toward, or away from, the corresponding pivot points 8, which latter are fixed in position, whereby to vary the distance between each pair of pivot points 8 and 9. This varies the degree of retardation exerted by each pair of brake shoes 5 and 6, as is obvious, and in the same manner as set forth in the Howe application above referred to. Springs 18 are employed to center the pairs of brake shoes for each track rail, in a symmetrical manner relatively to the rails.

As shown in Figs. 1 and 2, each of the brake beams 4 has an upstanding flange 19 projecting a short distance above the flat horizontal face 6 of its respective brake shoe.

Thus there is provided by the brake shoe and brake beam at the inner or wheel flange side of each rail, a flat horizontal surface with an upstanding flange at the edge, spaced from the wheel whereby, should a car passing through the retarder, climb out from between the brake shoes 5 and 6, it is prevented from riding off of the top of the retarder by the wheel flanges contacting with the projecting shoulders or flanges 19. In this manner it is quite out of the question for a car

which climbs out of a retarder to ride off of the retarder and cause damage of any kind.

In the form shown in Figs. 1 and 2 a standard form of brake beam is used, and the projection of flange 19, is obtained by decreasing the height of the inner brake shoe, by cutting a portion off of the vertical leg thereof, and hence the flanges 19 are shown at only the inner side of each rail.

10 Shown in Fig. 3 is a slightly modified form of the invention wherein the brake shoe 20 is of normal depth from top to bottom, and deeper than the inner shoes in Figs. 1 and 2, so that it would normally have its upper horizontal surface 20¹ in line with the highest point 22 of its shoe beam 21. In this form, however, the brake beam 21 is formed with the shoulder 22 of somewhat greater than normal height, whereby to project above the upper face 20¹ of one standard form of brake shoe 20, a distance substantially the same as occurs in Figs. 1 and 2.

Furthermore, this shoulder 22 can also be increased in width at its upper end, as at 22¹ in Fig. 3A, so as to extend inwardly over the face 20¹, toward the wheel flange, to thus decrease the possible wheel travel, in a lateral direction, if the wheel should climb out from between the brake shoes.

30 In other words, in Figs. 1 and 2 the shoe beam is standard and the inner brake shoe is shortened in a vertical direction so as to allow the shoulder 19 of its brake beam to project above the top face of the brake shoe 20 to thereby form a wheel retaining shoulder. In the form of Fig. 3, the brake shoe is standard and of usual height, and the brake beam, either the inner one only, or both, are modified from a standard configuration to the extent of slightly extending the upwardly projecting shoulder 22, so as to form the desired wheel retaining shoulder above the top face 20¹ of the brake shoe 20.

The above rather specific description of one form of this invention has been given solely by way of example, and is not intended, in any manner whatsoever, in a limiting sense. Obviously, this invention can assume many different physical forms, and is susceptible of various modifications, and all such forms and modifications are intended to be covered by the present invention, as come within the scope of the appended claims.

55 Having described my invention, I now claim:—

1. In a car retarder of the track brake type, in combination with a pair of running rails, a shoe beam at each side of each running rail, a brake shoe carried by each shoe beam, one of the shoe beams and shoe at each rail being formed to constitute a horizontal plane support face extending away from the rail with an upstanding shoulder at the rear thereof

and parallel to the rail of strength and height to prevent a derailment.

2. In a car retarder of the track brake type, in combination with a pair of running rails, a shoe beam at each side of each running rail, a brake shoe carried by each shoe beam, the shoe beam and shoe at the flange side of the track rail being formed to constitute a horizontal plane face extending away from the rail with an upstanding shoulder at the rear thereof and parallel to the rail.

3. In a car retarder of the track brake type, in combination with a pair of running rails, a brake shoe and a brake beam at one side of each rail, a substantially flat horizontal face on the brake shoe and a shoulder on the beam parallel with the rail and projecting above the face, whereby to prevent car wheels from running off of the tops of the brake shoes and to permit prompt rerailment of such wheels, in the event a car climb up onto the tops of the brake shoes.

4. In a car retarder of the track brake type, in combination with a pair of running rails a brake shoe and a brake beam at the flange side of each rail, a substantially flat horizontal face on the brake shoe and a shoulder on the beam parallel with the rail and projecting above the face, whereby to prevent car wheels from running off of the tops of the brake shoes and to promptly rerail such wheels, in the event a retarded car should climb up onto the tops of the brake shoes.

In testimony whereof I affix my signature.

WESLEY V. MORGAN.
